Attorney.

UNITED STATES PATENT OFFICE.

ISRAEL L. LANDIS AND JACOB RIDDEL, OF LANCASTER, PENNSYLVANIA;
SAID RIDDEL ASSIGNOR TO SAID LANDIS.

GATE.

SPECIFICATION forming part of Letters Patent No. 280,632, dated July 3, 1883.

Application filed November 4, 1882. (Model.)

To all whom it may concern:

Be it known that we, ISRAEL L. LANDIS and JACOB RIDDEL, of Lancaster, in the county of Lancaster, and in the State of Pennsylvania, have invented certain new and useful Improvements in Gates; and we do hereby declare that the following is a full, clear, and exact description thereof, reference being had to the accompanying drawings, and to the letters of reference marked thereon, making a part of this specification.

This invention has for its objects to provide a gate which may be bodily elevated when desired, and which may be adjusted at any desired angle, as more fully hereinafter specified. These objects we accomplish by the means illustrated in the accompanying drawings, in which—

Figure 1 represents a view showing the gate partly in section and partly in elevation. Fig. 2 represents a horizontal sectional view of the roller at the free end of the gate on the line *x* *x*; and Fig. 3 represents a sectional view of the hinge-post on the line *y* *y*, showing the slide and groove in which it works.

The letter A indicates the gate, which is constructed of two vertical beams and the pivoted parallel bars B, as indicated, the vertical beams being provided with horizontal wires C, loosely secured in suitable apertures, so as to permit the bars to move freely when adjusting the gate at an angle, as more fully hereinafter specified.

The letter D indicates two socket-heads provided with screw-threaded shanks which extend through one of the vertical beams aforesaid, and are confined by means of screw-nuts thereto.

The letter E indicates the gate-post, which consists of a vertical box having a longitudinal slot or opening, F, at one side. The said post on its interior is also provided with vertical grooves G, in which is located a slide, H, adapted to move vertically up and down. The said slide, near the upper and lower edges, is slotted, as indicated by the letter I, and in these slots are secured the adjustable pintle-heads K, which are provided with screw-threaded shanks and screw-nuts for the purpose of adjusting the pintle-heads vertically,

which is done by loosening the nuts and moving said pintle-heads up or down, and then clamping them, when in the desired position, by means of the nuts. The object of this adjustment is to set the said pintles at points 55 where they will coincide or register with the socket-heads, this being rendered necessary when it is desired to apply our improved post to an old gate-frame, in which it is found that the socket-heads are of varying distances apart. 60 The pintles set into the sockets in the socket-heads of the gate, forming hinges upon which the gate swings. Within the box, near the upper part, is located a drum, L, mounted on a shaft journaled in bearings in the sides of 65 gate-posts. One end of the shaft projects to the outside, and is provided with a crank, M, by which the shaft and barrel may be rotated. The said shaft is also provided with a ratchet-wheel, N, within the gate-post, with which is 70 adapted to engage a pawl, P, pivoted in a slot in the wall of the gate-post, one end projecting outward for the purpose of permitting the pawl to be operated to release the ratchet.

To the drum is secured a cord or chain, K, 75 which is also secured to the shank of the lower pintle-head or to the slide in such manner that upon rotating the drum the slide will be elevated or lowered, carrying the gate-body with the slide.

The letter S indicates two rods or wires secured, respectively, to the upper and lower corners of the gate-post in any convenient manner, preferably with screw-hooks, so that the tension of the rods or wires may be regulated. 85 The said rods or wires are connected by means of a chain, T, which passes over a roller, U, mounted on a screw-threaded stud, V, secured to one side of the gate. The said stud is provided with a binding-nut, W, having a crank, 90 X, by means of which the chain may be clamped to hold the gate when raised at an angle. In some instances, where it is desired to elevate the gate as high as possible, a pulley may be located near the top of the gate-post and the 95 elevating cord or chain passed over the same.

The letter Y indicates the latch, which slides upon one end of the central rail, its forward end being arranged to play under a bent guide, Z, the rear end being split and arranged to 100

play upon a bolt, A'. The said bolt is provided with a nut at its upper end, by means of which the latch may be securely held at any fixed position, while the rear end of the latch has elevations or lugs, which abut against the nut above alluded to when the latch is pushed forward, and prevent the loss or displacement of the latter should the nut not be screwed well down.

10. We are aware that it is not broadly new to provide a gate with a vertically-sliding beam secured to the hinge-post, and to which the gate is attached.

Having thus described our invention, what 15 we claim, and desire to secure by Letters Patent, is—

1. The combination, in a gate, of a hollow or mortised gate-post provided with vertical grooves and the vertically-movable slide to 20 which the gate is hinged, and the drum, ratchet and pawl, and the rope or chain connecting the drum and slide, and means for turning the

drum to lower or elevate the gate, substantially as specified.

2. In combination with the slide, slotted as 25 described, the adjustable pintle-heads, substantially as and for the purposes specified.

3. In combination with the gate constructed as described, the rods and chain and adjusting-hooks, the roller mounted on a screw-stud, 30 and the crank-nut and washer, substantially as specified.

4. In combination with the gate, the sliding latch slotted, as described, at its rear end, and bolt and nut, the whole applied substantially 35 as specified.

In testimony whereof we affix our signatures, in presence of two witnesses, this 3d day of October, 1882.

ISRAEL L. LANDIS.
JACOB RIDDEL.
